UNITED STATES PATENT OFFICE.

JOHN A. DOANE, OF WEST HARTFORD, CONNECTICUT, ASSIGNOR TO PRATT & WHITNEY COMPANY, OF NEW YORK, N. Y., A CORPORATION OF NEW JERSEY.

SIZING DEVICE FOR SURFACE GRINDERS.

Original application filed May 31, 1923, Serial No. 642,613. Divided and this application filed August 13, 1925. Serial No. 50,087.

This invention relates to surface grinding machines and in particular a sizing device therefor enabling an operator to determine the progress of and completion of the grinding operation, and is a division of my copending application Serial No. 642,613, filed May 31, 1923.

An object of the present invention is to provide a small member adjacent the work support adapted to be abraded by the work contacting surface of the wheel.

Another object of the invention is to mount an indicator on the member adjacent the work table, the indicator having its movable pointer actuated by an extension engaging the abraded surface of the member.

A further object of the invention is to provide means permitting said member to be fed a small amount after the completion of each grinding operation so that it will contact with and be abraded by the wheel during each successive grinding operation.

With these and other objects in view, my invention consists in the features of construction and operation set forth in the following specification and illustrated in the accompanying drawings.

In the accompanying drawings annexed hereto and forming a part of this specification, I have shown my invention embodied in a vertical surface grinder in which a vertically movable wheel abrades work mounted on a rotating table, the plane of which is fixed, but it will be understood that the invention can be otherwise embodied and that the drawings are not to be construed as defining or limiting the scope of the invention, the claims appended to the specification being relied upon for that purpose.

In the drawings:

Figure 1 is a front elevation of a surface grinder having the present invention applied thereto.

Fig. 2 is a front elevation of the parts forming the present invention upon an enlarged scale, portions being broken away to more clearly disclose the construction.

Fig. 3 is an outside front elevation of part of the construction shown in Fig. 2.

Fig. 4 is a plan view of the parts shown in Fig. 3, partly in section, and

Fig. 5 is a cross section taken upon line 5-5 of Fig. 2.

Briefly, and in its broadest aspect, my in-

vention comprises: first, a surface grinding machine having a work supporting table and a rotatable abrasive wheel, one of these members being mounted so that it can move toward the other during the grinding operation; second, a member mounted adjacent the work table and preferably rotatable at a slow speed; third, means to feed this member after each grinding operation so that it will be contacted by the wheel during each operation; and fourth, an indicator adapted to contact with the wheel engaging surface of the member.

Referring more in detail to the figures of the drawing, a vertical surface grinder is disclosed having a base 10 and column 11. Within the base 10 is a table 12 which may be rotated by any preferred or usual means. On the column 11 is a slidably head 13 carrying a rotatable grinding wheel 14 at its lower end. As these parts may correspond exactly to those disclosed in my copending application Serial No. 642,613, filed May 31, 1923, it is not thought that further description is necessary. The invention, it will be understood, is applicable to surface grinding machines in which either the wheel 14 is movable toward the work table 12 during operation or the work table 12 is moved toward the wheel 14. The former only of these forms of the invention is illustrated.

Adjacent the work table 12 is a relatively small member 15 on the upper end of a shaft 16. This member and its shaft 16 rotate about an axis parallel to the axis of rotation of the work table. The shaft 16, the rotating member 15 and attached parts are carried by a bracket 17 adjustably clamped to a guideway formed in a portion of the column 11. The shaft 16 may be rotated by means of a driving shaft 18 connected through bevel gears 19 and 20 to a sleeve 21 surrounding the shaft 16 carrying the rotatable member 15. The sleeve 21 is, as shown, splined to the shaft 16 so that the shaft 16 may be moved axially while it is being rotated. Preferably the member 15 on the upper end of the shaft 16 is removably attached so that other similar members may be easily substituted when one is worn out. It is made of any suitable material such as cast iron which may be readily abraded by the wheel 14 while acting upon the work blank W on the table 12. Also the upper end of

the rod or shaft 16 carrying the member 15 is provided with a flange so that it is supported on the upper end of a sleeve 24.

In order to adjust into position and feed the rotatable member 15 forwardly or upwardly after the completion of each grinding operation, the sleeve 24 is suitably supported in the bracket 17 and has an elongated threaded portion 25 on its lower end. Surrounding this sleeve 24 and engaging its threaded portion 15 is a gear 26. Meshing with the teeth of this gear 26 is a pinion 27 on the upper end of a splined shaft 28 supported within the bracket 17. In a supplementary bracket 29 a ratchet wheel 30 is provided splined to the shaft 28 and adapted to be engaged by a pawl 31 on a rod 32 movable within the bracket 29. The end of this rod 32 extends beyond the bracket 29 and may be engaged either by the hand of the operator or by a lever controlling the movements of parts of the grinding machine. With each longitudinal movement of the rod 32 or plunger the ratchet wheel 30 and the splined rod 28 are rotated slightly so that the sleeve 24 is slightly elevated by rotation of the gear 26 upon the threaded portions 25 of the sleeve 24. To prevent rotation of the sleeve 24 during rotation of the gear 26, a detent 32* is provided which is adapted to engage a short spline or recess formed in the sleeve 24. To remove the sleeve 24, if necessary, it is only required to remove the detent 32* from the recess or spline. For this purpose the detent 32* is mounted on a manually movable and spring pressed plunger 33.

From the above description it will be seen that a small rotatable and abradable member 15 is provided adjacent the work table 12 having a surface adapted to be engaged and abraded by the wheel 14. Also means are provided to rotate the member 15 and adjust its position vertically. By means of the bracket 17 supporting the sleeve 24 carrying the member 15 and attached parts, the position of the surface on the member abraded by the wheel 14 may be adjusted vertically. This adjustment is made each time the parts are set up for operation with work W of any one finished thickness. When one adjustment is made, however, it is not required to be changed until other work blanks of materially different thicknesses are operated on.

55 Adapted to contact with the upper surface of the rotatable member 15 is an extension 40 outstanding from a vertical rod 41. This rod 41 is supported within bearings 42 in an upward extension 43 to the bracket 17 supporting the sleeve 22 and its attached parts. The rod 41 is attached at its upper end to the movable member 44 of an indicator 45 fixed in position to the upper end of the bracket 17. The indicator 45 is, as shown, preferably of the dial type, in which a point-

er 46, moved by the vertical movement of the rod 41, is provided movable about a graduated dial. The position of the surface of the rotating member 15 therefore can be at all times determined after a first work blank 70 has been abraded and tested.

The operation of the indicating device will now be described. The bracket 17 is first adjusted to a position so that the rotating member 15 is slightly higher than the upper surface of a finished blank W. The surface of the member 15 contacted with by the wheel 14 will be abraded by the wheel as the wheel is fed downward during its operation upon the work W. When the work W has been reduced to its finished dimension the upper surface of the work W and the upper surface of the rotating member 15 will be at the same height, that is, in the same plane. The indicator 45 is then set by adjusting the length of the rod 40 so that, with the extension 40 resting upon the surface of the rotating member 15 when work has been completely ground, the pointer 46 will stand over the zero of the scale of graduations on the dial. When the finished work W has been removed and other blanks mounted on the table 12 the rotating member 15 is elevated by movement of the plunger 32 and rotation of the gear 26 on the threaded portion 95 of the sleeve 22. When the wheel 14 is again lowered to engage the work W it will engage and abrade the rotating member 15 before the final dimension of the work blank W is reached. The rotating member 15 will thereafter be abraded simultaneously with the work blank W, and, with abrasion of the rotating member 15 the indicator pointer 46 will be moved until, when the finished dimension of the work blank W is reached, the pointer 46 of the indicator will again stand over the zero of the graduated dial. During this period when the wheel 14 simultaneously abrades the work pieces W on the supporting table 12 and the rotating member 105 15, the pointer 46 of the indicator will indicate the progress of the grinding. With each successive operation upon blank W on the table 12 the rotating member 15 is worn away an amount equal to the distance it is 110 fed upwardly. After a number of operations the member 15 may be removed and a new one substituted and adjusted to position as stated above.

What I claim is:

1. A sizing device for surface grinders comprising in combination, a work supporting table, a wheel support, means to rotate said wheel, means to cause relative movement between said table and wheel support, a member adjacent the work table adapted to contact with and be abraded by the work contacting surface of the wheel, and an indicator having a movable bar in contact with the abraded surface of said member whereby 120

the reading of said indicator will determine the progress of the grinding operation.

2. A sizing device for surface grinders comprising in combination, a work supporting table, a wheel support, means to rotate said wheel, means to cause relative movement between said table and wheel support, a member adjacent the work table adapted to contact with and be abraded by the work contacting surface of the wheel, an indicator having a movable bar in contact with the abraded surface of said member whereby the reading of said indicator will determine the progress of the grinding operation, and
- 10 means to advance the member for successive grinding operations.

3. A sizing device for surface grinders comprising in combination, a work supporting table, a wheel support, means to rotate said wheel, means to move said wheel support toward said table during operation, a member adjacent said table adapted to contact with and be abraded by the work contacting surface of the wheel, means to rotate said member about an axis parallel to the axis of rotation of the work table during operation, and an indicator having a movable bar in contact with the abraded surface of said member whereby the reading of said indicator will determine the progress of the grinding operation.

4. A sizing device for surface grinders comprising in combination, a work support-

ing table, a wheel support, means to rotate said wheel, means to cause relative movement between said table and wheel support, a rotatable member adjacent said work table adapted to contact with and be abraded by the work contacting surface of the wheel, and a dial indicator having a pointer attached to a movable bar in contact with the abraded surface of said member whereby movement of said indicator pointer determines the progress of the grinding opera-

45

5. A sizing device for surface grinders comprising in combination, a work supporting and rotating table, a wheel support, means to rotate said wheel, means to cause relative movement between said table and wheel support during the grinding operation, a rotatable member adjacent the work table adapted to contact with and be abraded by the work contacting surface of the wheel, means to rotate said member about an axis parallel to the axis of rotation of said table, means to advance said rotatable member axially after each grinding operation, and an indicator having a movable bar in contact with said member whereby the reading of said indicator may determine the progress of the grinding operation.

In testimony whereof, I hereto affix my signature.

JOHN A. DOANE.
